UNITED STATES PATENT OFFICE.

ARTHUR L. GARNISS, OF SPRINGFIELD, MASSACHUSETTS, ASSIGNOR TO DENNISON MANUFACTURING COMPANY, OF FRAMINGHAM, MASSACHUSETTS, A CORPORATION OF MASSACHUSETTS.

CONTAINER.

Application filed October 24, 1927. Serial No. 228,123.

This invention relates to an improvement in a container and more particularly in a container comprising two cases, the inner case being nested in the outer case.

It is at times desired that the container in which merchandise is shipped should also be employed to display the merchandise on a counter or in a show window, and the primary object of this invention is to provide such a container having an inner case in which the merchandise is placed and which is adapted to be mounted in an outer case in two different positions, the first being that in which the merchandise is exposed, and the second being that in which the merchandise is concealed.

Throughout the specification and claims the first position will be referred to as the obverse position and the second position will be referred to as the reverse position.

Further objects will appear from the following specification, taken in connection with the drawings which form a part thereof, and in which

Fig. 1 is a front elevation of the container with the cases in the reverse position, in which merchandise is concealed;

Fig. 2 is a sectional view taken along the line 2—2 of Fig. 1;

Fig. 3 is a view similar to Fig. 2, the cases being in the obverse position in which the merchandise is exposed; and

Fig. 4 is a view similar to Fig. 3 to an enlarged scale, certain portions being broken away.

The container shown in the drawings and designated generally by the reference numeral 10 has been selected solely for the purpose of illustration, and not limitation. The container 10 comprises an outer case 11, and inner case 12 the dimensions of the two cases being such that the inner case can nest in and fit snugly within the outer case. The outer case 11 comprises a back wall 15, a bottom wall 16, side walls 17 and 18, and a top wall 19. The top wall 19 is provided with a flange 20 which extends across the front and along each side of the case and is hinged to the outer portion of the case 11 in any suitable manner, as for example by means of flexible hinge 21 attached to the under face of the top wall and the front face of the back wall. The inner case 12 comprises a back wall 25, a bottom wall 26, side walls 27, only one of which is

shown in the drawings, and a top wall 28. 55 Suitably secured in any desired manner to the outer case 11 is a base 30 having a continuous flange 31 which completely surrounds and encloses the lower end of the outer case 11,

It will be noted that the front of each of 60 these cases is open. The inner case 12 may be provided with any desired form of support 35 and lining 36, depending upon the contour of the article or articles to be enclosed therein. When the cases are nested in the 65 reverse position as shown in Fig. 2, the back wall 15 of the outer case 11 closes the open front of the inner case 12, and the back wall 25 of the inner case 12 fills the open front of the outer case 11. 70

That portion of the flange 31 of the case 30 standing across the open front of the case 11 engages the lower end of the inner case 12 and when the case is in the reverse position, as shown in Fig. 2, the flange also engages the 75 lower end of the back wall 25. The top wall 19 of the outer case is adapted to be raised as indicated by dotted lines in Fig. 2, in order to permit the insertion and removal of the inner case. After the inner case has been fixed 80 in position the top wall drops back into the full line position shown in Figs. 2, 3 and 4 and projects below the upper end of the inner case. Thus the flange 20 on the top wall 19 and the flange 31 on the base 30 function to 85 hold the inner case 12 in the nested position within the case 11. The function of these flanges is the same regardless of whether the cases are assembled in the obverse or in the reverse position. 90

It is thus evident that a container of this character is adapted to hold articles for convenient storage and shippage and to display the same for merchandising purposes. This container is made up of elements which may 95 be manufactured by machines and processes commonly known to the box-making art, its various component elements being similar to those which are commonly used in boxes but the novel relationship thereof permitting the 100 advantageous results indicated above.

I claim:

1. A container comprising an outer case, an inner case adapted to be removably nested in said outer case, a retainer extending over the 105 open side of the outer case to hold the inner case therein, a top wall hinged to the outer case, said wall having a flange normally ex-

tending downwardly over the end of the inner and outer cases, said hinged wall being movable to an open position wherein its flange no longer engages the cases and wherein it permits the inner case to be slid upwardly out of engagement with the retainer.

2. A container comprising an outer case, an inner case adapted to be removably nested in said outer case, and a flanged base secured to said outer case, the flange of said base surrounding the lower ends of both said cases when in nested position, said outer case having a flanged top wall hinged to the body portion thereof, the flange of said top wall extending below the upper edges of both cases when in the nested position.

3. A container comprising an outer case, an inner case adapted to be removably nested in said outer case in either obverse or reverse po-

sition and to receive merchandise, each case comprising bottom, back, side and top walls, the front of each case being open, and a flanged base secured to the bottom wall of said outer case and surrounding the lower ends of both said cases in either position, the top of said outer case being movably mounted, whereby in the obverse position the open fronts of said cases coincide to expose the merchandise, and in the reverse position the open front of said inner case is closed by the back wall of said outer case and the open front of said outer case is filled by the back wall of said inner case to conceal the merchandise.

Signed by me at Springfield, Mass. this 35
11th day of September, 1927.

ARTHUR L. GARNISSL
